UNITED STATES PATENT OFFICE

WALTER D. WRIGHT, OF TACOMA, WASHINGTON

FILM-FIRE EXTINGUISHER

Application filed August 29, 1927. Serial No. 216,017.

This invention relates to devices for extinguishing film fires, within the film cabinet of a motion picture projector.

An object of the invention is to put out a film fire, either automatically or by the act of the operator, before it gets beyond control and causes panic.

Another object is to put out the fire quickly enough to avoid the destruction of the film on the reel.

Another object is to avoid drenching the film with the extinguishing liquids used in my invention, in case the reacting fluids should get spilled and start action of the device in any other than the normal manner.

I attain these objects by means of the mechanism illustrated in the accompanying drawings, in which

Fig. 1 is a side elevation of the extinguisher tank, support and other parts, in upright inoperative position, with the film cabinet 15 seen in Figs. 2 and 4 removed.

Fig. 2 is a top view of the same, in conjunction with the film cabinet 15.

Fig. 3 is a vertical section of the tank and its trunnions on line 3—3 of Fig. 1; and

Fig. 4 is a side view of the complete device in its operative position.

The same numerals refer to corresponding parts in the different figures of the drawings.

My invention comprises a tank 1, supported on arms 2 extending forward from bracket 3, which may be secured to a wall or other stable support. The tank is pivotally supported by trunnions 4 and 5 in suitable bearings on arms 2. As seen in Figs. 1 and 2, the trunnions are off centre and below the centre of gravity of the tank, causing the tank to upset when not otherwise supported.

The tank is normally held in upright inoperative position by the end 6 of lever 7, which is pivoted at 8. The end 6 normally rests in a notch in block 9, which is attached to the tank wall off centre in the other direction, as seen in Figs. 1 and 2, supporting the tank in the position here shown until withdrawn from the notch.

Mounted on bracket 3 is a solenoid coil 10

with plunger 11, the latter being pivoted to lever 7 and normally held outward by spring 12, as seen in Fig. 2, so as to retain the end 6 in its notch.

Trunnion 5 is tubular and as seen in Fig. 3 is connected by elbow 13 with pipe 14 inside the tank, reaching nearly to the top of the tank. On the outside, the tubular trunnion 5 extends horizontally into the film cabinet 15, as seen in Fig. 2, terminated by a nozzle 16. While the tank is supported in inoperative position, nozzle 16 points away from the interior of cabinet 15, as seen in Fig. 2. In Fig. 4, the tank is shown upset into its operative position and where the wall of cabinet 15 is broken away the nozzle 16 is seen turned over and pointing toward the interior of cabinet 15.

The release of the tank to upset by gravity is brought about electrically, upon any considerable rise of temperature in cabinet 15. When a film fire occurs, it starts at the projector lens and rapidly travels up the film 17, Fig. 4, into cabinet 15, where much of the film of the picture may be contained on the reel, indicated in dotted lines at 18. If not immediately controlled, the fire will envelop the reel and develop into a conflagration which is apt to cause panic in the theatre. My invention provides means for immediately extinguishing the fire before it can get beyond control.

As the flame travels up film 17 into the cabinet, its heat first strikes thermostat 19 directly above it. Opening 20 at the other side of the cabinet provides a vent for encouraging the current of hot gases to run up in contact with the thermostat, then across the top of the cabinet and out opening 20.

As seen in Fig. 4, the thermostat may consist of two simple strips 21 of thermostatic metal, set in such relation that a rise of temperature causes their free ends to approach and make contact. The strips are separately secured by bolts 22 and 23, which pass through insulators 24 and 25 and serve as terminals outside the wall of cabinet 15.

To these terminals are connected the wires of the electric circuits shown, easily understood from Figs. 2 and 4, in which solenoid

10 is put in series with thermostat 19 and the leads 26 of a source of current. A shunt circuit may be provided, with switch 27, for manual control.

5 By this means, when a film fire starts, thermostat 19 closes the circuit, energizing solenoid 10, which pulls in its plunger 11 and withdraws the end 6 of lever 7 from the notch in block 9, upsetting the tank to its 10 operative position, as in Fig. 4. It is obvious that the closing of switch 27, by the operator, will accomplish the same result. A leaf spring 28 may be secured to bracket 3 to limit the swing of the tank when it 15 upsets.

15 The device is to be charged with any suitable fire extinguishing agents such as a solution of sodium carbonate 29, Fig. 3, nearly filling the tank, and an unstoppered bottle 30 of sulphuric acid, supported from cover 31. Upon upsetting of the tank, the two liquids 20 mingle, with violent formation of carbon dioxide gas, the resulting pressure forcing the solution to discharge through pipe 14, which 25 is now submerged since the tank is upset.

30 The solution and gas issue as a froth from nozzle 16, being spurted over the whole contents of cabinet 15, filling the cabinet with carbon dioxide gas and drenching the burning film, with the result that the fire gains little headway after entering the cabinet and 35 is quickly extinguished.

35 The invention is not intended to be limited to the form or any of the details shown or described, but is intended to embrace the scope of the following claims.

I claim:

40 1. The combination of a film cabinet and film reel therein with a fire extinguisher comprising a tank operable by rotation, a frame in which said tank is pivotally mounted, a spout rotatable with the tank extending angularly in respect to the direction of pivot from said tank into said film cabinet 45 adjacent a film reel therein, said spout directed away from said film reel when the tank is in inoperative position and directed toward said film reel when in operative position.

50 2. The combination of a film cabinet and film reel therein with a fire extinguisher comprising a tank operable by rotation, pivots supporting the tank, one of said pivots forming a conduit communicating with the tank and having an offset spout angularly disposed with respect to the axis of the pivot, said offset spout rotatable with the tank and 55 extending into the film cabinet, adjacent a film reel therein, said spout directed to discharge onto said reel upon the tank assuming an operative position and away from said reel upon the tank assuming an inoperative position.

60 3. The combination of a film cabinet and a film magazine therein with a fire extin-

guisher comprising a fire extinguisher tank, means for supporting said tank, a spout extending from said tank into said film cabinet and normally directed away from said magazine, and means for bringing said spout from 70 said normal position to a position directed toward said magazine.

4. The combination of a film cabinet and a film reel therein with a fire extinguisher comprising a tank operable by rotation, pivots 75 supporting the tank, one of said pivots forming a conduit communicating with the tank and having an offset spout angularly disposed with respect to the axis of the pivot, said offset spout rotatable with the tank and 80 extending into the film chamber adjacent a film reel therein, said spout directed to discharge onto said reel upon the tank assuming an operative position and away from said reel upon the tank assuming an inoperative 85 position, and other means for releasing said tank to an operative position.
